Inventor:

George Schubert.

UNITED STATES PATENT OFFICE.

GEORGE SCHUBERT, OF RUSHING, TEXAS.

PLUNGER FOR BALING-PRESSES.

SPECIFICATION forming part of Letters Patent No. 727,850, dated May 12, 1903.

Application filed July 6, 1901. Serial No. 67,309. (No model.)

To all whom it may concern:

Be it known that I, GEORGE SCHUBERT, a citizen of the United States, residing at Rushing, in the county of Tarrant and State of

5 Texas, have invented certain new and useful Improvements in Plungers for Baling-PresSES, of which the following is a specification, reference being had therein to the accompanying drawings, in which—

○ Figure 1 is a front view of a baling-press plunger provided with my improvement. Fig. 2 is a rear view of said plunger. Fig. 3 is a side view of same, showing the plunger in position in a baling-press, with the press partly broken away and in section to show the operation of the improvement. Fig. 4 is a section view taken on line 1 1, Fig. 5, showing the location of the trip and the bearings for same. Fig. 5 is a top plan view of the plunger with part of the top plate broken away to show parts below in full lines. Fig. 6 is a detail end view of the trip, and Fig. 7 is a detail side view of same.

My present invention relates to an improvement in a plunger for baling-presSES; and it consists in a trip so pivoted in the upper and front part of the body of the plunger in near a vertical position and with its upper end, at edge, projecting above the upper edge of the plunger, and remaining rigid in such position as the plunger moves inward, and to be pressed down beneath the upper level of the plunger as said plunger moves back or out from beneath the trough of the press, and thus avoid 35 the hanging of the plunger within the trough of the press.

In the drawings, A designates the body or bale-chamber of the press. (Shown in section in Fig. 3.)

40 A' is the hopper, mostly broken away.

B⁴ designates the face of the plunger.

B' and B² designate the slots for the retainers. (Not shown in the drawings.)

C designates the rollers journaled near the 45 edge and lower end of the plunger to travel on the lower plate of the press-body.

E is a center or hollow boss to receive the plunger-bar. (Not shown.)

F is the top plate or flange extending back 50 some distance.

H is a rib extending from the center boss down to the lower edge of the plunger. I I

are similar ribs extending from near each side of the boss E to the top plate F.

All the above are arranged as in common 55 use and will be readily understood.

a designates the face portion of the trip, having the lower portion b cut out, forming the ridge g and crease b, to allow of its turning down, as shown in dotted lines in Fig. 3, 60 and allow the front edge J of the plunger to run up higher.

d d are bearings formed on the lower edge of the trip a proper distance from each end, to be seated in the ribs I I of the plunger, 65 which are formed for this purpose.

The front and lower part g of the trip must be left full to form a joint with the face of the plunger or edge J.

The ribs I I are cut out far enough back to 70 allow of the placing of the trip and also far enough down below the edge J to form a bearing for the trip. This trip does not extend clear across the upper face of the plunger; but enough stock of the plunger is left on 75 each end of the trip to provide room for the upper retainer-slots B², as seen in Fig. 1, for the usual retainers.

h is a bar secured in near the center of the trip B and far enough from the upper edge 80 of the trip to be just beneath the upper plate F when the trip is in position and projecting with its free end rearward and curved to come with its free end to near the rear end of the boss E when the trip is closed, as seen in full 85 lines in Figs. 3 and 4.

i is a spiral spring of sufficient length to provide the necessary elasticity and secured with one end on the bolt i' and with its other end in the rear end of the bar h in a manner 90 to hold the trip closed up against the plunger.

The bearings of the trip are low enough beneath the edge J of the plunger and the bar h is near enough the plate F so that after the trip is put in place and the bar h secured in 95 the trip said trip cannot disengage from said opening of the plunger, and the heavier the pressure is on the upper and front edge of the trip the more rigid the trip will be, and the power of the spring i is so adjusted as to 100 hold the trip in a vertical position or closed after released from the downward pressure of the compressed material. The centers of the bearings d d of the trip are far enough back

from the vertical line of the downward pressure on the upper edge of the trip so that when a heavy downward pressure is exerted on the top edge of the trip it will aid in kicking the plunger back as soon as said plunger is released from any forward pressure and being pressed down by the compressed material to the position as seen in dotted lines in Fig. 3, and thus admit of the plunger going back from beneath the trough without hanging.

The size and proportions herein shown and described can be varied to suit the different material to be baled.

15 Having thus described my invention, what I claim as new, and desire to secure by Letters Patent, is—

1. In a plunger for a baling-press, the combination with a trip pivoted within the plunger and projecting upward with its free end to near a vertical position, a bar *h* secured in the trip and projecting rearward, means to secure said bar to the plunger-bar, as and for the purpose described.

25 2. In a plunger for a baling-press, the com-

bination with a trip pivoted within the plunger and projecting upward, with its free end to near a vertical position, a bar *h* secured in the trip and projecting rearward, a spring *i* secured to its rear end, and to the plunger, as 30 and for the purpose described.

3. In a plunger for a baling-press, the combination with a trip pivoted within the plunger and projecting upward, with its free end to near a vertical position, bearings *d d* on 35 said trip, ribs *I I* recesses formed therein for bearings, as and for the purpose described.

4. In a plunger for a baling-press the combination with a trip pivoted within the plunger and projecting upward with its free end 40 to near a vertical position, bearings *d d* on said trip, ribs *I I* recesses formed therein for bearings, a crease *b* and a projection *g* to engage with the edge *J*, as and for the purpose described.

GEORGE SCHUBERT.
